UNITED STATES PATENT OFFICE

CHRIS SCHRUM, OF LINCOLN, NEBRASKA

TIRE-VALVE-CORE-VENDING MACHINE

Application filed February 8, 1929. Serial No. 338,514.

This invention relates to a vending machine for valve cores used in the valve stems of pneumatic tires and the like, the general object of the invention being to provide means whereby a customer can secure a core by depositing a coin of the proper denomination into the machine and turning the handle of the machine.

This invention also consists in certain other features of construction and in the combination and arrangement of the several parts, to be hereinafter fully described, illustrated in the accompanying drawings and specifically pointed out in the appended 15 claim.

In describing the invention in detail, reference will be had to the accompanying drawings wherein like characters denote like or corresponding parts throughout the several views, and in which:—

Figure 1 is a front view of the device, showing the interior parts in dotted lines.

Figure 2 is a section on line 2—2 of Figure 1.

Figure 3 is a top plan view.

Figure 4 is a view similar to Figure 1, but showing the interior parts in a different position.

Figure 5 is a section on line 5—5 of Figure 2.

In these views, the numeral 1 indicates a casing which is divided by the partitions 2 into a large chamber and a small chamber. An inclined rack 3 is arranged in the large chamber, the rack comprising two members spaced apart to receive the cores, shown at A, between them, and as shown, the cores are held in upright position and they will gravitate toward the lower end of the rack.

40 A lever 4 has its upper end pivoted to a stub shaft 5 carried by the vertical partition 2, the lever being arranged within the large chamber, and the lower end of the lever is formed with the curved prongs 6 and 7.

45 The upper portions of the prongs are bent outwardly in opposite directions from the stem so that said prongs are spaced apart and the extremities of the prongs overlap. The lever is so arranged that its prongs 7 will extend across the path of the cores and

thus prevent the cores from moving on the rack, but when the lever is moved to the right, the prong 7 will move out of the path of the cores and the prong 6 will be in the path of the cores and as the prongs are spaced apart a distance slightly greater than the diameter of the core, one of the cores will move into the space between the prongs and be held by the prong 6. Then when the lever is moved to the left, the prong 6 will release the first core so that this core can drop from the rack, but the core next to the first one will be engaged by the prong 7, so that but one core can drop from the rack. Thus the oscillation of the lever controls the discharge of the cores from the rack and permits but one core at a time to drop from the rack.

55 A shaft 8 is journaled in the walls of the front or small chamber, with its rear end passing through the vertical partition 2 and links 9 connect this shaft with the upper part of the lever 4. An arm 10 is fastened to the shaft and extends downwardly into engagement with the periphery of a disk 11 60 fastened to a shaft 12 which is also journaled in the walls of the small chamber and extends through the front wall where it receives a knob 13. The disk has a coin receiving notch 14 therein which, when the disk is in a certain position, will be located below the lower end of a coin chute 15 which depends from the top of the casing, so that a coin dropped into the chute will enter the notch with a portion projecting above the disk, so that 65 when the disk is turned, this portion of the coin will contact the arm 10, thus pushing the arm outwardly. This movement of the arm will partly rotate the shaft 8 and cause the links 9 to move the lever 4 to a position 70 where the prong 6 will release a core. When the disk is turned to a position to move the coin out of contact with the arm 10, a spring 16, which engages the lever, will return the parts to normal position. The coin will 75 finally drop from the notch into the bottom of the small chamber, from which the coins can be removed by opening the door 17 in the front of the chamber, this door being provided with a lock 18. Ratchet means, 80

85

85 The upper portions of the prongs are bent outwardly in opposite directions from the stem so that said prongs are spaced apart and the extremities of the prongs overlap. The lever is so arranged that its prongs 7 will extend across the path of the cores and

90

90 A lever 4 has its upper end pivoted to a stub shaft 5 carried by the vertical partition 2, the lever being arranged within the large chamber, and the lower end of the lever is formed with the curved prongs 6 and 7.

95 The upper portions of the prongs are bent outwardly in opposite directions from the stem so that said prongs are spaced apart and the extremities of the prongs overlap. The lever is so arranged that its prongs 7 will extend across the path of the cores and

100

shown generally at 19, prevent retrograde movement of the disk and the shaft 12 and the cores dropping from the rack, will fall upon a chute 20 which will deliver the cores to a tray 21 at the front of the casing.

5 The top 22 of the casing is removable so that cores can be placed on the rack and this top is secured in position by the lock 23.

10 From the foregoing it will be seen that I have provided simple means whereby one can secure a valve core by depositing a coin in the device and turning the handle. The device can be placed anywhere desirable, such for instance, on an exterior wall of a 15 garage, so that the customers can secure valve cores without going into the garage and even if the garage is closed.

20 It is thought from the foregoing description that the advantages and novel features of the invention will be readily apparent.

25 It is to be understood that changes may be made in the construction and in the combination and arrangement of the several parts, provided that such changes fall within the scope of the appended claim.

What I claim is:—

30 A dispensing device of the class described comprising a diagonally arranged rack for holding the articles to be vended, a forked lever pivotally supported and having its prongs curving toward each other, with the prongs bent outwardly in opposite directions beyond the longitudinal plane of the lever, with the extremities of the prongs overlapping, the lower end of the rack extending 35 between the prongs and means for oscillating the lever to release the lowest article on the rack while holding the next article on the rack.

40 In testimony whereof I affix my signature.
CHRIS SCHRUM.
